IV BY Alfred T. Brattin

UNITED STATES PATENT OFFICE

2,097,166

PORTABLE WATER HEATER

Julius L. Stone, Philadelphia, Pa.

Application September 12, 1935, Serial No. 40,218

1 Claim. (Cl. 219—39)

This invention relates in its broader aspects to power producing apparatus or units and more particularly to a portable assemblage adapted for the operation of what may be classified as 5 domestic heating, cooling or lighting devices, and analogous means or apparatus. More specifically the assemblage to be hereinafter described relates to a portable water heater for household and analogous use; or, for use in places where hot 10 water is not provided such as in hotel rooms equipped with running water service only; although by detaching the heater unit, the remainder of the assemblage can be employed for operating suitable means for cooling or freez- 15 ing purposes; or for illuminating purposes.

The primary object of this invention is to provide a compact assemblage which when coupled to a conventional cold water outlet or a spigot, and the water is turned on, automatically generates the necessary current for operating a heater. Another object is to provide an assemblage of 20 the type indicated which is adapted for heating water proportionately with the flow thereof through the power producing unit thereof.

A further object is the provision of a portable assemblage of the type indicated which includes 25 a rotor, operable by the running water, and adapted to actuate a generator of electric current for heating a resistance coil entwined about a spiralized water heating tube.

A still further object is to provide a water heating assemblage of the character specified, which is simple to construct, reliable and efficient in 30 action, comparatively compact in size, readily set 35 up for use, and just as easily disassembled for package and transportation in a suitcase or other receptacle.

With the foregoing and other objects in view, this invention consists in the features of construction, combination and arrangement of parts 40 hereinafter fully described, illustrated by the accompanying sheet of drawings, and finally claimed; it being understood that various changes 45 in the details of construction and other applications or combinations of the related parts may be resorted to, without departing from the spirit and scope of said invention.

In the drawing:

Fig. I is a broken assembly elevation of a 50 portable water heater embodying the present invention.

Fig. II is side elevation of the same.

Fig. III is a vertical section taken approxi- 55 mately as indicated by the arrows III—III on Fig. I.

Fig. IV is a section on the plane designated IV—IV in Fig. III; and

Fig. V is a section taken substantially as indicated by the arrowed plane V—V also in Fig. III.

In all the views corresponding parts are indicated by the same reference characters.

Referring more in detail to the drawing the novel portable water heater therein illustrated comprises a power unit 1, a generator of electric energy or current 2, and a heater unit 3.

The power unit 1 preferably consists of a cylinder 4 having end closures 5 suitably secured to flanges 6 on said cylinder with interposition of appropriate gaskets to prevent leakage. Integral with the end closures 5 are housings 7 for 15 ball bearings 8 affording rotative support for a drive shaft 9, with a fly-wheel 10 fixed to one end and having its other end squared, or otherwise shaped, at 11 for attachment thereto, as by means of a coupler 12 threadedly engaged on an extension 13 of the associated housing 7, of one end of a flexible shaft 14, the other end of said shaft being similarly connected by a coupler 15 to the shaft 16 of the electric current generator 2. Conventional packing glands 9' are fitted 20 around the shaft 9 to prevent ingress of water to 25 the bearings 8, as readily understandable.

Suitably secured on the drive-shaft 9 within the cylinder 4 is a cupped rotor 17, the cups 18 whereof are tangentially directed relative to the axis 30 of rotation, and adapted for filling with water by way of an inlet 19, fitted with a cupped connector 20, in turn adapted for frictional engagement on the spout 21 of a conventional water-service spigot 22. In order to support the power unit 1 35 in engagement with the spigot spout 21, said unit is provided with loops 23 for application thereto of a flexible support or belt 24 provided with a fastener 25, whereby the unit 1 is operatively connected to the spigot 22, in an obvious manner.

Integral with the power unit 1 is a projecting bracket 26 affording removable connection for the heater unit 3. This unit 3 preferably consists of a casing 27 with inset end closures 28, and having a thermo-insulating liner 29 to preclude 45 escape of heat therefrom. Centrally within the casing 27 is a spiral water coil 30 having one end 31 connected by an elbow coupler 32, to the flow outlet 33 from the power unit 1, while its other end 34 projects through the thermo-insulated 50 bottom of said casing, as a discharge for the heated water.

The spiralized portion of the water coil 30 is preferably encased in a suitable body of heat conducting material, such as a comparatively 55

- stout cylinder 35 of compressed asbestos or analogous substance, about and through which is appropriately entwined a resistance or heater element 36, the terminals 37 whereof are appropriately bridged to a pronged-outlet or current connector 38 on the upper wall of the heater casing 27. Adapted for "plug" application to the pronged outlet 38 is a socket 39 at one end of a conductor cable 40; the other end of said cable being attached to the brush-holder 41 of the generator 2, whereby current produced by the latter is transmitted to the resistance or heater element 36 in a clearly apparent manner needing no further explanation herein.
- 42 is a conventional mounting in the heater casing 27 for bridging the ends of the resistance 36 in current conducting relation with the prong outlet wires 37, all in accordance with practice well known in the art.
- From the foregoing the operation of the improved portable water or other liquid heater will

clearly be apparent without further description herein. It is also to be distinctly understood that other adaptations or applications of the invention may be made without departing from the spirit and scope of the following claim.

Having thus described the invention, I claim:

A portable water heater comprising a closed casing having a cylinder of insulating material therein, the sides and ends thereof being spaced from the adjacent walls of the casing, a coiled water conducting tube embedded in the cylinder and having one terminal fixed in one wall of the casing and constituting a water inlet, and its other terminal fixed in another wall of the casing and constituting a water outlet, said terminals serving to rigidly support the cylinder spaced from the walls of the casing, and an electrically heated resistance coil entwined about the cylinder and in the bore thereof.
